UNITED STATES PATENT OFFICE.

THOMAS DINGLEY, OF PARNELL, NEW ZEALAND.

COAL-SKEP.

1,259,274.

Specification of Letters Patent. Patented Mar. 12, 1918.

Application filed July 12, 1917. Serial No. 180,182.

To all whom it may concern:

Be it known that I, THOMAS DINGLEY, a citizen of the Dominion of New Zealand, and residing at Cleveland Road, Parnell, in the Provincial District of Auckland, in the Dominion of New Zealand, have invented certain new and useful Improvements in Coal-Skeps, of which the following is a specification.

10 This invention relates to scoops or skeps employed for moving coal and more particularly for loading and unloading coal into and from steamers and other vessels, and provides improvements whereby a triangular shaped scoop is made with a door at the back the hinge of which is incased and protected against the pressure of the coal, the door being normally closed and secured by a pivoted bar, and the scoop made with a flare so that a plurality can be nested together.

The drawing herewith illustrates the invention and will now be referred to for the purposes of a detailed description:—

25 Figure 1, is a side elevation with part removed,

Fig. 2, is a plan, and

Fig. 3, a rear elevation of the scoop.

The scoop is made of sheet iron or steel 30 and has a flat bottom 1 with a turned up lip 2 at its front end. The sides 3 and 4 are approximately triangular in shape as shown in Fig. 1, and are provided with brackets 5 having eyes 6 to which chains 7 are attached 35 for slinging the scoop from a crane or the like.

The back of the scoop comprises a plate 8 uniting the sides 3 and 4 at their upper part.

40 Below the plate 8, the back of the scoop is closed by a door 9 hinged by pintles 10 to the sides 3 and 4, the lower edge of which closes against the bottom of the scoop.

The door 9 is secured in its closed position 45 by a crossbar 11, pivoted at its middle part upon a pin 12 and adapted to pass into keeper bracket 13. The ends of the bar are adapted to pass behind horns or hooks 14 formed integral with or secured to a stiffening band 15, which passes around the back end of the scoop. The horns or hook 14 are reversed in order that they may receive the ends of the bar 11 when turned on its pivot 50

12. The hinged upper edge of the door 9 is enclosed in a housing 16 which protects the 55 said edge or hinge from pressure of the coal in the scoop. The housing is made of iron or steel plate bent to form a semicircular hood, wherein the top edge of the door may turn freely.

60 The sides 3 and 4 are made with a slight flare as shown in Figs. 2 and 3, so that the upper parts of the sides are a greater distance apart than their lower parts. By flaring in this manner, a plurality of scoops 65 can be nested together.

The scoop is filled while the door 9 is held closed by the bar 11 and while the scoop is resting on its bottom 1. The scoop is then lifted by its chains 7, which are so arranged 70 that the top edges of the sides 3 and 4 are horizontal when the scoop is so lifted. The weight of the coal presses upon the door 9, except where shielded by the housing 17, and when the bar 11 is turned on its pivot 75 12 free from the horns 14, the coal pushes open the door 9 and slips readily down the now sloping bottom 1 and back 8 until the scoop is quite empty.

What I do claim and desire to secure by 80 Letters Patent of the United States is:—

1. A metal scoop comprising a body portion U-shape in cross section and connected at its rear upper portion by a transverse bar and open at the front, a reinforcing 85 band extending around the rear edge of the scoop and terminating above the bottom of the transverse bar, the lower edge of the transverse bar being curved inwardly between the sides of the scoop to form a 90 housing, a door the upper end of which is located in the housing, pintles extending from the upper portion of the door and extending through alined openings formed in the rear sides of the scoop and the reinforcing bar, a latch pivoted to the door and extending beyond the sides of the scoop, and catches extending from the reinforcing bar 95 to hold the ends of the latches.

2. A scoop open at its front end and comprising a bottom, angular sides, a transverse bar connecting the angular sides at the rear upper portion, the space formed below the transverse bar serving as a door opening, the lower edge of the transverse bar 100 105 between the angular sides being curved in-

wardly to form a housing, a door in the door opening, the upper end of the door being terminated in the housing, pintles extending from the upper ends of the door and operating in openings formed in the sides, a latch bar pivoted to the door, catches projecting from the rear edges of the scoop and with which the ends of the latch bar engage.

In testimony whereof I have signed my name to this specification in the presence of 10 two witnesses.

THOMAS DINGLEY.

Witnesses:

D. A. McCONNELL,
ALAN MCNEIL.
